UNITED STATES PATENT OFFICE.

GLENN E. McFADDEN, OF LAKEWOOD, OHIO, ASSIGNOR TO ALFRED VESTER SONS, INC.,
OF PROVIDENCE, RHODE ISLAND, A CORPORATION OF RHODE ISLAND.

LIGHTING FIXTURE.

Application filed December 18, 1923. Serial No. 681,317.

To all whom it may concern:

Be it known that I, GLENN E. McFADDEN, a citizen of the United States, residing at Lakewood, in the county of Cuyahoga and 5 State of Ohio, have invented a certain new and useful Improvement in Lighting Fixtures, of which the following is the specification.

My invention relates to that class of lighting fixtures in which an artificial candle is employed, with the design to imitate a real candle.

There are, at present, two types of candles employed in lighting fixtures, one of which 15 is just the plain white cylindrical tube generally formed of vitrified fibre, although sometimes they are formed of glass or porcelain. The other type is that in which the simulation is carried out to a most perfect 20 degree by embossment which reproduces the simulation of the melted wax running down the side of the candle and terminating in a slightly enlarged portion ending in a drop. This type of imitation candle is quite 25 expensive, having to be moulded in moulds which require the highest class of workmanship to construct.

My invention has for its object to provide a metal embossment which can be placed on 30 top of vitrified fibre and which, when sprayed, cannot be told from the highest priced imitation candles in which the embossment is moulded thereon.

My means of accomplishing the foregoing 35 object is readily seen in the accompanying drawings which are hereto annexed and are a part of this specification:

Fig. 1 is a view of a tube, having my metal embossment partially mounted thereon.

Fig. 2 is a similar view of the same, a portion being broken away.

Figs. 3, 4, 5 and 6 are detail views of my improved metal embossment.

The same reference numerals refer to similar parts throughout the entire description.

As shown in the drawings, the vitrified cylinder 1, which is to be used in the place of a candle, is formed with a smooth exterior. I have shown it in connection with an electric lighting fixture which is not described, as obviously it forms no part of my invention. My improved metal embossment 2 is then cast or stamped in the configuration shown in the detailed view with a lip 3 which 55 engages a shoulder 5 formed on the cylinder

adjacent its upper end or it may be extended over the end of the cylinder and rest or hang thereon. It is secured to one end of the tube 1 and wrapped around, as clearly shown in Fig. 3 until the two ends meet, when a drop 60 of solder will hold it securely in its circular position or it may be formed into the annulus first and slipped down over the cylinder 1 until the lip 3 engages the end of the cylinder 1 and it will be thus held in position, 65 although other means of fastening, of course, may be employed, as found desirable. Although I have shown a continuous lip 3 it will be apparent that a number of inwardly extending projections will serve as well, if 70 desired.

The entire tube and metal embossment is then sprayed with the standard enamel employed for this purpose, with the result that when completed it cannot be distinguished 75 from the highest priced moulded tube, although it may be produced for a very small fraction of the cost of same and thereby places it within the reach of the general public at a price which they can afford to 80 pay.

It will be apparent to persons skilled in the art that my invention is not confined to any specific design for the embossment. There may be any number of the drips 3, 85 which simulate the melted tallow of the candle and also that it may be cast, stamped, moulded or otherwise formed without deviating from the spirit of my invention, and I do not desire to be understood as limiting 90 myself to the specific designs shown or the manner in which the metal embossment is described as being made except as such limitations as may appear in the herein appended claims.

1. In a device of the character described, the combination with a cylindrical tube of metal embossment simulating melted wax, a lip formed on said metal adjacent its top which engages the end of the cylindrical 100 tube when in position.

2. In a device of the character described, the combination with a cylindrical tube with an annulus of metal simulating melted wax, an inwardly extending lip thereon, so that it will hang from the end of the tube when slipped over it.

3. In a device of the character described, the combination with a cylindrical tube of metal embossment simulating melted wax, 110

a projection which extends inwardly when said metal embossment is formed into a ring which projection engages the end of said tube for the purpose set forth.

5. 4. In a device of the character described, the combination with a cylindrical tube of a metal embossment simulating melted wax,

a shoulder on said tube adjacent one end, a lip formed on said metal adjacent its top which engages the said shoulder when said metal embossment is in position. 10

Dated Nov. 30, 1923.

GLENN E. McFADDEN.
